CLOSURE FOR CONTAINERS

Rollin L. Drake, Port Arthur, Tex., assignor to
 The Texas Company, New York, N. Y., a corporation of Delaware

Application August 19, 1931, Serial No. 558,023

4 Claims. (Cl. 113—121)

This invention relates to closures for containers and refers more particularly to sealing means and closures for metallic receptacles.

The principal object of the invention is to provide sealing and closure means which will be simple, efficient and inexpensive. The invention contemplates a method of crimping into a body member having an opening formed therein, a neck which may be used in conjunction with a spout, cap or plug.

The invention will be better understood in connection with the accompanying drawing wherein:

Figure 1 is a sectional elevation showing a body member and a closure element, and a preferred form of apparatus for carrying out the object of my invention.

Figure 2 is an enlarged view of the body member and the closure element before crimping.

Figure 3 illustrates the operation of crimping the body member and the closure element together to form a seam.

Figure 4 shows a body member with closure element complete, comprising a screw neck adapted to serve as an outlet for a container, a cap or plug therefor, and a metal seal adapted to be pressed into the opening in the container after filling.

Figure 5 is a bottom plan view of the punch used in the crimping operation.

Referring to the drawing, a body member 10, preferably a can top, is provided with an opening therein and a peripheral upwardly extending flange 12 is formed at said opening. A closure element comprising a neck 13, is provided with an annularly bent peripheral flange 14 adapted to fit closely about the opening and rest against the flange 12. As shown in Figure 2, the neck 13 is preferably preformed and threaded to receive a spout, cap or plug, as may be desired.

In carrying out my invention I have provided a movable punch 15 and a die 16 adapted to have a relative telescopic movement in order to engage the upturned flanges 12 and 14 to bend them outwardly and to then flatten the juxtaposed flanges to firmly secure the neck 13 to the body member 10. The punch 15 and die 16 are mounted in a press of suitable construction which I have illustrated as comprising a base member 17 to which the die 16 is attached by means of a suitable screw 18, and a vertically movable plunger 19 at the lower end of which is formed the punch 15. The punch 15 is provided with a rounded portion 15a and a plurality of small projections 15b, the purpose of which will be brought out hereinafter. A cylindrical sleeve 20 is mounted

within the base member 17 and die 16 and is pressed upwardly by means of a suitable compression spring 21. A second sleeve 22 secured to a rod 23 through a pin 24 movable within a slot 24a is mounted to have sliding engagement with the punch 15 and is pressed downwardly by means of a compression spring 25.

In assembling the various parts, the body member 10 is placed upon the die 16 with the flange 12 surrounding the upper end of the sleeve 10 20. The neck 13 is then placed upon the body member 10 with the flange 14 surrounding the flange 12 as shown more clearly on Figure 2. The punch 15 is then moved downwardly and the rounded portion 15a engages the inner flange 12 15 and bends the two flanges outwardly. Continued downward movement of the die causes the flanges 12 and 14 to be flattened as shown in Figure 3 and a tight seam is thus produced by means of which the neck 13 is securely attached to the body member 10. The spring pressed sleeve 22 20 engages the upper rim or edge of the neck 13 and holds it in position during the crimping operation. The sleeve 20 serves to position the body member 10 and, of course, slides freely downward upon being engaged by the punch 15.

In order to prevent possible relative movement between the neck 13 and the body member 10 the projections 15b are provided and extend downwardly at spaced intervals about the lower edge 30 of the punch 15. The projections 15b serve to indent the seam produced by bending outwardly the flanges 12 and 14 and thus prevent any relative rotational movement between the neck 13 and member 10.

It has been found that the closure described herein is very efficient, however, if desired a suitable sealing composition may be employed to make the container leak tight. Thus, sealing material may be inserted underneath the annularly bent peripheral flange 14, for example, prior to the crimping operation. In the case of containers intended for volatile or inflammable fluids, such as petroleum oils, particularly the lighter products thereof, it is generally desirable 40 to use a sealing material.

Referring to Figure 4, it is contemplated that the screw neck 13, which may serve as an outlet or pouring spout for a container the top of which may be the body member 10, may be used 50 in connection with a metal plug or cap 26 and a metal seal 27, adapted to be pressed into the opening in the container top after filling. The cap 26 is formed with a recess at 28 in which a washer 29 of suitable resilient packing such as 55

cork is inserted to make a leak-tight joint between the cap 26 and the neck 13. The metal seal 27 may be pressed tight in the opening by hand after filling. A small amount of sealing compound may be employed if desired.

Obviously many modifications of my invention may be made without departing from the spirit and scope thereof, and I therefore intend no limitation except as imposed by the appended claims.

I claim:

1. The method of attaching a closure element to a container which comprises, providing a body member having an opening therein and an upwardly extending annular flange about the periphery of said opening, providing a neck which may serve as a pouring outlet for the container and having adjacent its lower end an inwardly extending radial flange, said flange being turned upwardly at its inner edge, positioning the neck over the opening in the body member so that the upwardly extending flange of the neck surrounds and rests against the upwardly extending flange of the body member, exerting pressure to bend the juxtaposed flanges outwardly and continuing the application of pressure to flatten the bend against said body member to thereby form a seam attaching the neck to the body member.

2. The method of attaching a closure element to a container which comprises, providing a body member having an opening therein and an upwardly extending annular flange about the periphery of said opening, providing a neck which may serve as a pouring outlet for the container and having an inwardly extending radial flange and an upwardly extending axial flange, positioning the neck over the opening in the body mem-

ber so that the upwardly extending flange of the neck surrounds and rests against the upwardly extending flange of the body member, exerting pressure to bend the juxtaposed flanges outwardly and continuing the application of pressure to flatten the bend to thereby form a seam attaching the neck to the body member and indenting the seam at a plurality of points to prevent relative movement between the neck and the body member.

3. In a container, a body member having an opening therein, an upwardly extending neck adapted to serve as a pouring outlet for the container, said neck having adjacent its lower end an inwardly extending annular flange resting upon the body member about the said opening, said flange being crimped back upon itself at its inner edge, said body member having about the said opening an upwardly and then outwardly extending flange crimped over the said neck flange to fasten the neck to the body member.

4. In a container, a body member having an opening therein, an upwardly extending threaded neck adapted to serve as a pouring outlet for the container, said neck having adjacent its lower end an inwardly extending annular flange resting upon the body member about the said opening, said flange being crimped back upon itself at its inner edge, said body member having about the said opening an upwardly and then outwardly extending flange crimped over the said neck flange to form a seam fastening the neck to the body member, a metal seal pressed into the said opening and resting upon said seam, and a metal cap screwed into said neck.

ROLLIN L. DRAKE.
